(57) **CLAIM**

The ornamental design for the unified image display for a video terminal including a gaming machine, as shown and described.

DESCRIPTION

FIG. 1 is a front-side perspective view of the display according to the present invention showing an example of content displayed thereon;

FIG. 2 is a front view of the display of FIG. 1 *with the environmental graphical user interface removed for clarity*;

FIG. 3 is a right side view of the display of FIG. 1;

FIG. 4 is a left side view of the display of FIG. 1;

FIG. 5 is a rear view of the display of FIG. 1; [and,]

FIG. 6 is a top view of the display of FIG. 1 with the environmental graphical user interface removed for clarity; and,

FIG. 7 is the front-side perspective view of the display of FIG. 1 with the environmental graphical user interface removed for clarity.

The broken lines showing [portions of a] the environmental graphical user interface in FIG. 1 and the remainder of the terminal cabinet [to support the display of the present invention] in FIGS. 1-[6] 7 are provided for [illustrative] the purposes [only] of illustrating the environmental structure and form no part of the claimed design.

1 Claim, 7 Drawing Sheets

Matter enclosed in heavy brackets [ ] appears in the original patent but forms no part of this reissue; matter printed in italics indicates the additions made by reissue.
